UNITED STATES PATENT OFFICE.

CLARENCE A. PETTERSON, OF SAN ANSELMO, CALIFORNIA, ASSIGNOR OF ONE-HALF TO
JACOB GOLINSKY, OF SAN FRANCISCO, CALIFORNIA.

FOLDING PAPER BOX.

1,132,877.

Specification of Letters Patent. Patented Mar. 23, 1915.

Application filed July 15, 1913. Serial No. 779,120.

To all whom it may concern:

Be it known that I, CLARENCE A. PETTERSON, a citizen of the United States, residing at San Anselmo, in the county of Marin and 5 State of California, have invented new and useful Improvements in Folding Paper Boxes, of which the following is a specification.

My invention relates to the manufacture 10 of boxes made of flexible material, and is especially designed for the manufacture of rectangular boxes adapted to contain cakes and the like.

It consists in the formation of a blank 15 properly scored and foldable to form a box.

It also comprises details of construction which will be more fully explained by reference to the accompanying drawings, in which—

20 Figure 1 is a plan view of the blank. Fig. 2 shows the blank with the ends 2^a folded inwardly to lie flat upon the main portion. Fig. 3 is a perspective view of one of the corners, including the sides, ends and foldable angular reinforce. Fig. 4 is a perspective view showing the box partly folded. Fig. 5 is a view of the box complete, with cover partly closed.

25 For the manufacture of a box of this description, I employ cut-out blanks of paste-board or similar stiff, flexible material to form a bottom A and a cover B. With the bottom of the box are formed the sides 2 and ends 2^a, scored, as at 3, so as to be easily 30 folded from their original flat condition to form the vertical sides. The joining of the meeting angles is effected by means of rectangular ends, as at 4, which are in line with the ends 2^a of the box and are separated 35 from the sides 2 by slits, as at 5. These ends 4 are scored, as at 6, in lines diagonal from the bottom of the box to the opposite corner of the portion 4. The slits 5 and the score 3 allow the end portions 2^a to be first turned 40 up into a vertical position; the part 4 being at the same time folded so as to extend inside of the sides 2. The triangular portions of the part 4, shown in Fig. 1, extending from 6 to 5, will then have one of the 45 straight sides resting upon the bottom of the box and the other one vertical therewith.

These triangular portions are then glued or pasted down against the side of the box, thus holding the parts together, and the diagonal score 6 allows the outer portion of 55 the triangle to remain free, as shown plainly in Fig. 4. In this condition the sides may be flattened down; the scores 6 of the corners allowing the outer portions of these corners to be flattened down so that the sides 60 and ends lie upon the bottom, as plainly shown in Figs. 2 and 4.

The cover of the box is formed of the main section B of a size sufficient to cover the box portion when the sides of the latter are upright. The cover portion has sides 8 extending beyond the bottom line and having scores, as at 9, about which they may be folded into a position at right angles with the part B.

70 10 is a flap formed at the outer end of the cover portion and capable of being turned down when the cover is bent over the body of the box and thus forms a complete enclosure.

75 It will be seen that the sections 4, formed between the box and the cover and scored similarly to those at the outer end of the box, will allow the cover to be turned over and folded flat upon the bottom A. This 80 enables many boxes to be piled up in a flat condition which occupy but little space.

To assemble the box it is only necessary to turn the folded sides up about the scores 6 of the corner portions. Then in a similar 85 manner, after the contents have been enclosed, the cover is turned over the box. This provides a simple, readily formed box using a minimum amount of material, and the box is easily assembled for use.

90 Having thus described my invention, what I claim and desire to secure by Letters Patent is—

A folding paper box consisting of a blank 95 scored to form a bottom, an outer end and sides for the bottom, a cover with an inner end connecting the cover and bottom, sides on the cover and a flap on the cover, the extremities of the inner end having a pair of parallel slits and the outer end having a 100 single slit at each extremity thereof, said slotted portions on the opposite sides of the

blank being diagonally scored in opposite directions to form free triangular parts which are secured to the inner faces of the sides at points between the extremities of the sides whereby the latter will project over and extend beyond the slotted parts and will be engaged by the sides of the cover when the box is assembled.

In testimony whereof I have hereunto set my hand in the presence of two subscribing 10 witnesses.

CLARENCE A. PETTERSON.
